CLAIM

The ornamental design for a fence frame connector, as shown and described.

DESCRIPTION

FIG. 1 is a perspective view of my new design showing a fence frame connector;

FIG. 2 is a front elevation view thereof;

FIG. 3 is a rear elevation view thereof;

FIG. 4 is a right side elevation view thereof, the other side being a mirror image;

FIG. 5 is a top plan view thereof; and,

FIG. 6 is a bottom plan view thereof.

The portions of the article depicted in broken line form no part of the claimed design.
